UNITED STATES PATENT OFFICE.

WILLIAM WYLIE ARNOLD, JR., OF MANCHESTER, GEORGIA.

CARDING MACHINERY.

Application filed May 5, 1923. Serial No. 636,917.

To all whom it may concern:

Be it known that I, WILLIAM WYLIE ARNOLD, Jr., a citizen of the United States, and a resident of Manchester, in the county 5 of Meriwether and State of Georgia, have invented certain new and useful Improvements in Carding Machinery, of which the following is a specification.

This invention relates in general to carding machinery, and more particularly to an automatic sliver evener adapted to be organized with such machinery.

As is well known, cotton carding machines have to be stripped from two to 15 four times per day depending on the amount of cotton carded per day and the grade of the same in order to do good carding. When stripping a card you stop the cotton in lap form from feeding into the machine 20 and proceed to strip the cylinder and doffer by means of stripping rolls or a vacuum stripping system of all cotton and other foreign matter which has become embedded in the wire cloth on the cylinder and doffer. 25 Heretofore in the art after the stripping operation has been completed the feed roller is started so that the cotton lap is fed into the card wherein the cotton fibres are combed or carded and are delivered by 30 means of the doffer or coiler head into a can which is placed in front of the machine. It has been found however that when starting the machine up after the stripping operation the weight per yard of the first few 35 yards of sliver is very light owing to the fact that a great deal of the cotton which is fed into the machine is being pressed into the wire clothing of the cylinder and thus is utilized to charge the cylinder and is not taken therefrom by the doffer. As soon as 40 the cylinder fills up or has become charged the weight per yard of the sliver taken therefrom by the doffer reaches the average weight for which the machine is set to produce but this correct average weight is not 45 produced until about fifty yards of sliver has been delivered from the machine after the stripping operation. Such light weight and non-uniform sliver makes very uneven 50 and a very poor grade of yarn. For example, it has been found that where the average weight per yard of the sliver produced under ordinary operating conditions before stripping was fifty-nine grains with 55 a variation in weight of four grains per yard, the weights ranging from fifty-seven

to sixty-one grains per yard on a sixty-yard test then after stripping card machine, the first yard delivered weighed thirty-two grains and forty-eight yards were delivered 60 before the machine reached fifty-eight grains. It will be noted from these findings that the first yard delivered after the stripping operation with the ordinary machine 65 will run about forty-five per cent light.

The object of the present invention is to provide an automatic sliver evener adapted to be organized with carding machines and which when so organized is effective to overcome the aforementioned difficulties and 70 disadvantages and to enable the carding machine to produce a uniform and high grade product as well immediately after the stripping operation as during normal operation. For instance with the same machine whose 75 performance has been noted above but after having organized therewith the automatic sliver evener constituting the present invention, the weight of the first yard delivered after the stripping operation was found to 80 be sixty grains with a variation in weight per yard of two and one-half grains in a twenty yards test, the lightest weight per yard being fifty-seven and one-half grains. When the automatic sliver evener constituting 85 the present invention is in use the weight per yard runs more evenly immediately after stripping than it does with the ordinary machine ordinarily equipped when operating under normal conditions. 90

A further object is to provide a device of this character and having the foregoing advantages and which is also of simple and durable construction, reliable and efficient in operation and adapted to be organized with conventional carding machinery without necessitating serious or expensive alterations.

Other objects and advantages of the invention reside in certain novel features of 100 the construction, combination and arrangement of parts which will be hereinafter more fully described and particularly pointed out in the appended claims, reference being had to the accompanying drawings forming part of this specification and in which:

Figure 1 is a diagrammatic view, in plan, showing the relation of the automatic sliver evener constituting the present invention to 110 certain of the major elements of a carding machine;

Figure 2 is a fragmentary and diagrammatic view in side elevation of a portion of the carding machine equipped with the present invention;

5 Figure 3 is a view in side elevation, showing the automatic mechanism whereby the feed roll is driven from the doffer or is driven independently thereof;

10 Figure 4 is a view in section taken approximately on line 4—4 of Figure 3 and looking in the direction of the arrows;

15 Figure 5 is a view in rear elevation of the parts of the invention shown in Figure 3, the view being taken looking to the right end of Figure 3;

Figure 6 is a detail perspective view of the keeper bar for the automatic shifting lever; and

20 Figure 7 is a detail view illustrating the connection of the hand lever and sleeve of the automatic shifting mechanism.

25 Referring to the drawings it will be seen that the carding machine is shown diagrammatically and it is to be understood that it may be of any conventional construction. In the drawings it is shown as including a frame 5 upon which is mounted and suitably driven a main cylinder 6. At the rear end of the machine is a licker-in 7 and a feed 30 roller 8 and at the front end of the machine and cooperating with the main cylinder is a doffer 9. The main cylinder, licker-in, feed roller and doffer have shafts 10, 11, 12 and 13, respectively, which it is to be understood are suitably journaled on the frame 5 and project at their ends beyond the frame.

35 The licker-in 7 is driven from the shaft 10 of the main cylinder 6 by a cross belt 14 trained over pulleys fixed to the shafts 10 and 11. Means is provided for driving the doffer from the licker-in and includes a gear wheel 17 secured to the shaft 13 and adapted to be driven from a pinion 18 fixed to one end of a short shaft 19. The short shaft 19 is rotatably mounted in a bearing provided in a depending bracket 20 integral with a vertically swinging arm 21 on one end of which arm 21 is pivotally mounted, as at 22, on the frame 5. A hand lever 23 is suitably mounted on a bracket 24 and cooperates with the free end of the arm 21 and controls its position and incidentally controls the engagement or disengagement of the pinion 18 and gear wheel 17. The short shaft 19 which has fixed thereto the pinion 18 also has fixed thereto a pulley 25 driven by a belt 26 from the licker-in. This arrangement thus far described is conventional and standard in all respects.

40 Means is provided for driving the feed roll from the shaft 13 of the doffer cylinder when desired and preferably the feed roll is driven from the shaft 13 of the doffer cylinder at all times except during the period 45 which follows immediately after the strip-

ping. For this purpose a shaft 30 is provided and has one end geared, as at 31, to the shaft 12 of the feed roller 8. On the opposite end of the shaft 30 from that which is geared to the feed roll 8 a sleeve 32 is mounted so as to be at all times constrained to rotate with the shaft 30 while free to be shifted longitudinally or axially with respect thereto. In order to effect this mounting (see Figure 3) the sleeve 32 is slotted longitudinally, as at 33, and in the slot 33 a pin 34 is received, the pin 34 being fixed to the shaft 30. Obviously other means may be employed for so mounting the sleeve 32 on the shaft 30. One end of the sleeve 32 has secured thereto a beveled gear wheel 35 adapted to be brought into mesh with a co-acting beveled gear wheel 36 fixed to the shaft 13 of the doffer cylinder on the end of this shaft 13 opposite from the ring gear 17. When the gears 35 and 36 are in mesh the feed roll 8 is driven from the doffer 9. With the present invention it is proposed to drive the feed roll independently of the doffer immediately after the stripping operation, the doffer being allowed to remain stationary whereby the main cylinder may be charged or filled up to the requisite depth to obtain sliver of proper weight. In order to carry out these purposes a large gear wheel 38 is also fastened to the sleeve 32. The gear wheels 35 and 38 are spaced from each other and their hubs 35^a and 38^a define an annular groove 37 between them, the function of which will hereinafter fully appear.

50 When the sleeve 32 is shifted in one direction on the shaft 30 as for instance to the left as viewed in Figure 3, the beveled gears 35 and 36 will be disengaged and the large beveled gear 38 will be brought into engagement with a small beveled gear 39 fixed to a vertical shaft 40 adjacent the upper end thereof. The vertical shaft 40 is mounted at its lower end in a spindle bearing 41 and at its upper end it is rotatably mounted in a bearing 42 provided in a bearing bracket 43 secured to the frame 5, as shown in Figures 3 and 4. The vertical shaft 40 is driven from a jack shaft 45 extending transversely across the machine by beveled gears 46 to provide for a speed reduction, the jack shaft 45 being held for rotating movement, as at 47, in the frame and carrying at its end opposite the vertical shaft 40 a large spur gear wheel 48 which is so disposed that the pinion 18 is adapted to be brought into mesh therewith. It will thus be understood that the pinion 18 is selectively engageable with either the gear wheel 17 of the doffer cylinder or with the spur gear wheel 48 of the jack shaft so that the motion received by the pulley 25 from the belting 26 may be transmitted to the doffer cylinder or may be transmitted through the gear wheel 48, jack shaft 45, 130

gears 43, vertical shaft 40 and pinions 38 and 39 to the shaft 30, from whence it is transmitted to the feed roll.

Shifting mechanism is provided for controlling the engagement of the pinions 35 and 36 and 38 and 39 and this shifting mechanism preferably includes a hand lever 50 pivotally mounted, as at 51, to a bracket 52. The portion of the hand lever 50 pivotally mounted on the bracket has secured thereto and movable therewith a lateral arm 53 upon which a weight 54 is adjustably mounted. In order to provide for the connection of the hand lever to the hub 37 and consequently to the sleeve 32 a collar 55 is loosely mounted in the annular groove 37 and has secured thereto a two part clamp, one of the parts of the clamp 56 carrying a lateral pin 57 which is fitted in an opening 58 provided therefor in a hand lever 50. The arrangement is such that the gears 35 and 36 may be disengaged by a manual shifting of the hand lever 50 and of course by such shifting the gears 38 and 39 are engaged but when however the gears 38 and 39 are to be disengaged and the gears 35 and 36 engaged the operation is entirely automatic. For this purpose the lever 50 has fixed thereto a spring dog 60 co-operable with teeth or notches 61 provided in an arm 62 carried by the frame extension. As shown in Figure 6 the notches 61 have inclined faces 61^a and vertical faces 61^b so that the lever may be shifted to the left as viewed in Figure 3 without interference from the spring dog since it snaps over the inclined walls 61^a of the notches. Reverse movement of the lever, that is a movement from left to right, as viewed in Figure 3 can only be had when the spring dog 60 has been pressed away from the arm 62 and thereby withdrawn from the notches 61.

Automatic tripping or releasing mechanism is provided for releasing the spring dog 60 that is for retracting it from engagement with the notches 61 and permitting the weight 54 to return the lever to its extreme right hand position as shown in Figure 3. This releasing mechanism includes a shaft 65 rotatably mounted in bearings provided on the frame extension and arm 62 and having fixed to one end thereof a large gear wheel 66 meshing with a small gear wheel 67 fixed on a countershaft 68 rotatably mounted on the frame extension. The countershaft 68 also has fastened thereto a large gear wheel 69 with which a small gear wheel 70 fixed to the sleeve 32 is adapted to engage when the gears 38 and 39 are engaged and the gears 35 and 36 are disengaged that is when the gears are shifted to the left as viewed in Figure 3. It is to be noted that the gearing between the pinion 70 (which being fixed to the sleeve 32 is thus indirectly fixedly connected to the shaft 30) and shaft 65 is of such ratio as to very materially re-

duce the speed of the shaft 65 with respect to the shaft 30 so that the shaft 65 turns very much more slowly than the shaft 30 and consequently very much more slowly than the feed roller. In order to permit of the necessary variation in the relative speeds of the shaft 65 and the feed roll the countershaft 68 is mounted in an adjustable bearing in the frame extension as indicated at 71, in Figure 4 so that various sizes of gears 67 and 69 may be employed. A cam 75 is loosely mounted on the shaft 65 and includes a lateral and longitudinally extending finger 76 at its periphery engageable with the spring dog 60. An actuator 77 is provided for the cam and is secured to the shaft 65 by a set screw 78 and is provided with a laterally extending pin 79 engageable with the cam 75 to rotate the same with the shaft 65. The cam 75 is held against longitudinal displacement in one direction by the actuator 77 and is held against longitudinal displacement in the opposite direction by a collar 80. With this arrangement the shaft 65 and consequently the shaft 30 and feed roll can partake of considerable rotation while the feed roll is being driven independently of the doffer through the gear wheels 38 and 39 for the actuator 77 can move through a substantially complete revolution before its pin 79 engages the cam 75 to rotate the same and the cam can be so located on the shaft relative to this actuator that it passes through a part or the whole of another revolution before its pin 76 presses against the spring dog 60 to retract the same and permit the weight 54 to disconnect the gear 38 from the gear 39 and to bring the gears 35 and 36 into mesh and thus to drive the feed roll. The disengagement of the gears 38 and 39 is accompanied by the disengagement of the gears 69 and 70 since the gears 70 and 38 are carried on the same sleeve.

Braking mechanism is provided for stopping the shaft 65 as soon as the pinions 69 and 70 are disengaged and thus holding the cam and its actuator in its proper position ready for the next operation. This braking mechanism includes a braking element 85 slidably mounted on the arm 62 and connected to the hand lever 50 by its apertured lug 86 which is connected to brake 85 and moves therewith and a connecting rod 87 which is pivotally secured to the hand lever and which extends through the aperture of the lug 86. Nuts 88 are threadedly connected with the rod 87 and engage the lug 86 on the opposite sides thereof whereby adjustment may be made to secure the desired degree of braking action and to compensate for wear.

When it is desired to carry out the stripping operation the hand lever 23 is raised so that the swinging arm 21 is lowered and the pinion 18 is disengaged from the gear wheel 17 of the doffer whereby the feed

roll is stopped since the drive is transmitted to the feed roll through the doffer in the normal operation of the machine. When the doffer is being stripped the hand lever 50 is moved to the left, as viewed in Figure 3, and is engaged with the middle notch of the arm 62, the spring dog 60 locking the arm 50 in such position against retrograde movement. When the stripping operation has been completed and normal operation of the machine is to be resumed the hand lever 50 is shifted to the extreme left hand position as viewed in Figure 3 so that its spring dog 60 engages in the third notch 61. This shifting of the arm 50 brings the gears 38 and 39 into engagement so that the feed roll is then driven from the pulley 25 through the gears 18 and 48, jack shaft 45, beveled gears 46, vertical shaft 40 and beveled gear wheels 38 and 39. The feed roll then operates to feed the cotton to the main cylinder but the doffer is not operated to take the cotton from the cylinder at this time. Moreover when the feed roller 25 is so operated it is moved very slowly for it is being actuated through the speed reduction and thus the cotton is fed at a low rate of speed into the card so that the card has more time in which to spread the cotton into an even sheet adapted to uniformly charge the cylinder. During this time the shaft 65 is also being driven though more slowly than shaft 30 and the cam actuator 77 is being rotated around into engagement with the cam so that subsequently and at a time when the main cylinder has been properly charged the cam 75 will be actuated and its finger 76 pressed into engagement with the spring dog 60 to move the dog out of its notch 61 thereby releasing the lever 60 and permitting the weight 54 to move the lever 50 and consequently the sleeve 32 to the extreme right as viewed in Figure 3 so as to bring the gears 35 and 36 into mesh and so as to disengage the gears 38 and 39. The hand lever 23 is then lowered to raise the arm 21 and move the pinion 18 out of engagement with the pinion 48 into engagement with the gear wheel 17 so as to drive the doffer from the pulley 25 and drive the feed roll from the doffer as in the normal operation of the device. With this arrangement the carding machine may be stripped as often as found desirable and at the same time a high grade product is obtained for the sliver is of uniform and requisite weight and quality. A guard 90 for the gears 69 and 66 is mounted on the bracket 43.

60 I claim:

1. A carding machine including a feed roll and a doffer and comprising means for driving the feed roll from the doffer having gears adapted to be engaged or disengaged, means for driving the feed roll in-

dependently of the doffer and automatic shifting mechanism for rendering said last mentioned means inactive and for engaging the gears when the feed roll has been rotated a predetermined extent by said means. 70

2. A carding machine including a feed roll and a doffer and comprising means adapted to drive the feed roll from the doffer or to be rendered idle, supplemental driving mechanism independent 75 of the first mentioned driving means for actuating the feed roll and automatic shifting mechanism for rendering the supplemental driving mechanism idle after a predetermined period and rendering the 80 first named driving mechanism capable of driving the feed roll from the doffer during the normal operation of the machine.

3. A carding machine having a feed roll and a doffer, gearing for driving the feed roll from the doffer including a shaft geared to the feed roll, a gear connected to the doffer and a movable gear mounted on the shaft and engageable with the gear of the doffer, driving mechanism for rotating the feed roll independently of the doffer and including a gear mounted on the shaft of the gearing and constrained to partake of the sliding movement of said movable gear thereon engageable with the gear of the doffer and automatic shifting mechanism for rendering the driving mechanism idle and rendering the gearing active when the feed roll has been rotated to a predetermined extent. 95

4. A carding machine having a feed roll and a doffer, gearing for driving the feed roll from the doffer including a shaft geared to the feed roll, a gear connected to the doffer and a movable gear mounted on the shaft and engageable with the gear of the doffer, driving mechanism for rotating the feed roll independently of the doffer and including a gear mounted on the shaft of the gearing and constrained to partake of the sliding movement of said movable gear thereon engageable with the gear of the doffer and automatic shifting mechanism for rendering the driving mechanism idle 105 and rendering the gearing active when the feed roll has been rotated to a predetermined extent, said shifting mechanism including a hand lever having releasable means for securing the same in position to render the driving mechanism active and the gearing idle and being weighted whereby it is returned to position to render the gearing active and the driving mechanism idle when said releasable means is released, and means actuated by the shaft of the gearing for releasing said releasable holding means when the feed roll has rotated to the predetermined extent. 110

5. A carding machine having a feed roll and a doffer, gearing for driving the feed 115 roll from the doffer including a shaft geared to the feed roll, a gear connected to the doffer and a movable gear mounted on the shaft and engageable with the gear of the doffer, driving mechanism for rotating the feed roll independently of the doffer and including a gear mounted on the shaft of the gearing and constrained to partake of the sliding movement of said movable gear thereon engageable with the gear of the doffer and automatic shifting mechanism for rendering the driving mechanism idle and rendering the gearing active when the feed roll has been rotated to a predetermined extent. 120

65 6. A carding machine having a feed roll and a doffer, gearing for driving the feed 125 roll from the doffer including a shaft geared to the feed roll, a gear connected to the doffer and a movable gear mounted on the shaft and engageable with the gear of the doffer, driving mechanism for rotating the feed roll independently of the doffer and including a gear mounted on the shaft of the gearing and constrained to partake of the sliding movement of said movable gear thereon engageable with the gear of the doffer and automatic shifting mechanism for rendering the driving mechanism idle and rendering the gearing active when the feed roll has been rotated to a predetermined extent. 130

- roll from the doffer including a shaft geared to the feed roll, a gear connected to the doffer and a movable gear mounted on the shaft and engageable with the gear of the doffer, driving mechanism for rotating the feed roll independently of the doffer and including a gear mounted on the shaft of the gearing and constrained to partake of the sliding movement of said movable gear 5
- 10 thereon engageable with the gear of the doffer and automatic shifting mechanism for rendering the driving mechanism idle and rendering the gearing active when the feed roll has been rotated to a predetermined extent, said shifting mechanism including a hand lever having releasable means for securing the same in position to render the driving mechanism active and the gearing idle and being weighted whereby it is returned to position to render the gearing active and the driving mechanism idle when said releasable means is released, means actuated by the shaft of the gearing for releasing said releasable holding means when 15 the feed roll has rotated to the predetermined extent and comprising a shaft driven from the shaft of the gearing, and a cam actuated from the shaft of the shifting mechanism and engageable with the releasable holding means. 20
- 25 6. A carding machine having a feed roll and a doffer, gearing for driving the feed roll from the doffer including a shaft geared to the feed roll, a gear connected to the doffer and a movable gear mounted on the shaft and engageable with the gear of the doffer, driving mechanism for rotating the feed roll independently of the doffer and including a gear mounted on the shaft of the gearing 30 and constrained to partake of the sliding movement of said movable gear thereon engageable with the gear of the doffer and automatic shifting mechanism for rendering the driving mechanism idle and rendering the gearing active when the feed roll has been rotated to a predetermined extent, said shifting mechanism including a hand lever having a releasable means for securing the same in position to render the driving mechanism active and the gearing idle and being weighted whereby it is returned to position to render the gearing active and the driving mechanism idle when said releasable means is released, means actuated by the shaft of the gearing for releasing said releasable holding means when the feed roll has rotated to the predetermined extent and comprising a shaft, changeable speed reduction gearing for driving the shaft of the shifting mechanism from the shaft of the gearing, a cam loosely mounted on the shaft of the shifting mechanism, a cam actuator 35 fixed to the shaft of the shifting mechanism and cooperable with the cam, said cam being engageable with the releasable holding means to effect release thereof. 40
- 45 7. A carding machine having a feed roll and a doffer, gearing for driving the feed roll from the doffer including a shaft geared to the feed roll, a gear connected to the doffer and a movable gear mounted on the shaft and engageable with the gear of the doffer, driving mechanism for rotating the feed roll independently of the doffer and including a gear mounted on the shaft of the gearing and constrained to partake of the sliding movement of said movable gear thereon engageable with the gear of the doffer and automatic shifting mechanism for rendering the driving mechanism idle and rendering the gearing active when the feed roll has been rotated to a predetermined extent, said shifting mechanism including a hand lever having a spring dog, said shifting mechanism having a frame extension including an arm provided with notches cooperable with the spring dog for securing the hand lever in position to render the driving mechanism active and the gearing idle, said hand lever being weighted whereby it is automatically returned to position to render the gearing active and the driving mechanism idle when the spring dog is disengaged from the notches of said arm, and means actuated by the shaft of the gearing for disengaging the spring dog from the notches when the feed roll has been rotated 50 55 60 65 70 75 80 85 90 95 100 105 110 115 120 125 130
7. A carding machine having a feed roll and a doffer, gearing for driving the feed

- to a predetermined extent and comprising a shaft driven from the shaft of the gearing and a cam actuated from the shaft of the shifting mechanism and having a finger engageable with the spring dog for pressing the same out of engagement with the notches.
9. A carding machine including a feed roll and a doffer, means for driving the feed roll from the doffer, and means for driving the feed roll independently of the doffer.
10. A carding machine having a feed roll and a doffer, gearing for driving the feed roll from the doffer including a shaft geared to the feed roll, a gear connected to the doffer and a movable gear mounted on the shaft and engageable with the gear of the doffer, driving mechanism for rotating the feed roll independently of the doffer and including a driven gear mounted on the shaft and constrained to partake of the motion of the movable gear and a driving gear engageable with the driven gear, the driven gear being adapted to be positioned with the movable gear in neutral position in which both the driven and movable gears are disengaged from the gears with which they coact, the movable gear being disengaged from the gear with which it coacts when the driven gear is engaged with the driving gear and the driven gear being disengaged from the driving gear when the movable gear is engaged with which it is adapted to coact, a lever connected with the movable gear and with the driven gear for controlling the same, a spring detent and a rack bar associated with the lever for holding the same in adjusted position and adapted to prevent return movement of the lever from neutral position in which both the movable gears and driven gears are disengaged from the gears with which they coact until after the lever has been shifted to engage the driven gear with the driving gear, and means operated from the shaft of the gearing for releasing the spring detent after the driven and driving gear have been engaged for a predetermined period.

11. A carding machine having a feed roll and a doffer, gearing for driving the feed roll from the doffer including elements adapted to be connected and disconnected, one of the elements being shiftable for this purpose, driving mechanism for rotating the feed roll independently of the doffer and including a driven shiftable element associated with the shiftable element of the gearing and constrained to partake of the movement

thereof, the said shiftable elements being adapted to be shifted in neutral position as well as in a position to render the gearing active and the driving mechanism inactive and in position to render the gearing inactive and the driving mechanism active, controlling means for the shiftable elements, means for holding the controlling means in adjusted position and adapted to prevent return actuation of the controlling means to render the gearing active after the parts have been positioned in neutral position, said means necessitating positioning of the parts and enabling the driving mechanism to be active after neutral positioning of the parts.

12. A carding machine having a feed roll and a doffer, gearing for driving the feed roll from the doffer and including elements adapted to be connected and disconnected, one of the elements being shiftable for this purpose, driving mechanism for rotating the feed roll independently of the doffer and including a driven shiftable element associated with the shiftable element of the gearing and constrained to partake of the movement thereof, the said shiftable elements being adapted to be shifted in neutral position as well as in a position to render the gearing active and the driving mechanism inactive and in position to render the gearing inactive and the driving mechanism active, and controlling means for the shiftable elements.

13. In a carding machine, the combination with a carding cylinder, a feed roll, a doffer and means for concurrently driving the same, of means for arresting the operation of the feed roll during the stripping of the carding cylinder, means for arresting the operation of the doffer after the stripping operation, and means for driving the feed roll at a relatively slow rate of speed to recharge the carding cylinder after the stripping operation.

14. In a carding machine, the combination with a carding cylinder, a feed roll, a doffer and means for concurrently driving the same, of means for arresting the operation of the feed roll during the stripping of the carding cylinder, means for arresting the operation of the doffer after the stripping operation, means for driving the feed roll at a relatively slow rate of speed to recharge the carding cylinder after the stripping operation, and automatically operated means for discontinuing the charging operation after a predetermined period.

WILLIAM WYLIE ARNOLD, JR.
